CONTROL PANEL FOR KITCHEN SINK OR SIMILAR ARTICLE

Henry Dreyfuss, South Pasadena, Calif., assignor to
Crane Co., Chicago, Ill., a corporation of Illinois

Application July 7, 1958, Serial No. 51,688

Term of patent 14 years

(Cl. D49—1)

Fig. 1 is a perspective view of a control panel for kitchen sink embodying my new design; and
Fig. 2 is a front elevational view thereof.
The letters and numerals shown in broken lines are for illustrative purposes only.

I claim:

The ornamental design for a control panel for kitchen sink or similar article, substantially as shown and described.
